CLAIM

(22) **Filed:** **Jul. 10, 2020**

The ornamental design for an electronic device with display screen and graphical user interface, as shown and described.

(51) **LOC (14) Cl.** **14-04**

DESCRIPTION

(52) **U.S. Cl.**

The patent or application file contains at least one drawing executed in color. Copies of this patent or patent application publication with color drawing(s) will be provided by the Office upon request and payment of the necessary fee.

(53) **USPC** **D14/486**

The FIGURE shows a view of an electronic device with display screen and graphical user interface.

(58) **Field of Classification Search**

The even-dashed broken lines showing the electronic device with display screen and portions of the graphical user interface, including all icons shown and all text shown outside of the dot-dashed boundary lines, illustrate portions of the article of manufacture that form no part of the claimed design. The white dot-dashed broken line rectangle on the left side of the display screen, and the two black dot-dashed rectangles on the right side of the display screen, illustrate the bounds of the claimed design and form no part thereof. The lighter grey ghosted areas appearing outside of the dot-dash broken lines illustrate portions of the graphical user interface that form no part of the claimed design.
